DESIGN FOR A SUCTION CLEANER CASING

Jack Pickford and Raoul A. Lambert, Springfield, Mass., assignors to Westinghouse Electric Corporation, a corporation of Pennsylvania

Application March 23, 1949, Serial No. 1,579

Term of patent 14 years

(Cl. D9—2)

To all whom it may concern:

Be it known that we, Jack Pickford and Raoul A. Lambert, citizens of the United States, residing, respectively, at Springfield, in the county of Hampden and State of Massachusetts, and at Springfield, in the county of Hampden and State of Massachusetts, have invented a new, original, and ornamental Design for a Suction Cleaner Casing, of which the following is a specification, reference being had to the accompanying drawing, forming a part thereof.

Fig. 1 is a perspective view of a suction cleaner casing, showing our new design;

Fig. 2 is a side view thereof; and

Fig. 3 is a front view thereof.

The dominant feature of the design resides in

the portion shown in full lines on the drawing.

We claim:

The ornamental design for a suction cleaner casing, substantially as shown and described.

JACK PICKFORD.

RAOUL A. LAMBERT.
